UNITED STATES PATENT OFFICE.

CHARLES W. GRAHAM, OF ALLENDALE, NEW JERSEY, ASSIGNOR TO AMERICAN CAN COMPANY, OF NEW YORK, N. Y., A CORPORATION OF NEW JERSEY.

MACHINE FOR AND METHOD OF LINING CAN ENDS.

1,392,492.

Specification of Letters Patent.

Patented Oct. 4, 1921.

Application filed July 30, 1917. Serial No. 183,396.

To all whom it may concern:

Be it known that I, CHARLES W. GRAHAM, a citizen of the United States, residing in Allendale, in the county of Bergen and State of New Jersey, have invented a new and useful Improvement in Machines for and Methods of Lining Can Ends, of which the following is a specification.

This invention relates in general to machines for assembling thin, flat paper or similar gaskets with can ends to produce can ends having paper lined flanges adapted to be interfolded with the flanges of the can bodies to form hermetic closures for said bodies.

A principal object of the present invention is the provision of a machine of this character adapted for use in small establishments requiring only a few hundred or a thousand lined ends per day.

My invention contemplates the construction of a simple semi-automatic machine for assembling gasket liners and can ends, which will be cheap to construct, consist of few parts, and which may be operated, if desired, without power equipment. Gasket lining machines embodying my present invention are intended for use by the packers of products, who pack too few cans per day to justify the use of the relatively higher speed, full-automatic can end lining machines provided for use in the establishments of the larger packers.

A further object of the invention is the provision of a manually controlled and operated semi-automatic machine which may be used by unskilled attendants after a few simple instructions.

Other objects and advantages of the invention will be apparent as it is better understood from the following description when considered in connection with the accompanying drawing illustrating a preferred embodiment thereof.

On the drawing,

Figure 1 is an isometric view of the upper portion of the machine showing can ends and cut gasket liners on opposite sides of the assembling station, and the operator's hands approaching each other to bring them into assembling relation;

Fig. 2 is an isometric view of the complete machine, showing a gasket liner and a can end in assembling relation and the

operator's foot just touching the treadle to assemble the gasket with the can end;

Fig. 3 is a vertical section through the assembling head, showing the parts in the same position as in Fig. 2;

Fig. 4 is a like vertical section showing the assembling plunger in a partially descended position just engaging the gasket liner and the lower can end plunger elevated to hold the can end up to the orifice through which the gasket is passed in assembling;

Fig. 5 shows a like sectional view to Figs. 3 and 4 but with the assembling plunger fully depressed and the gasket liner seated in the recess of the flange of the can end.

Fig. 6 is a sectional view similar to Fig. 3 but showing a different position of some of the parts as the plunger is ascending from the position of Fig. 5.

Fig. 7 is a vertical sectional view at approximately right angles to that shown in Figs. 3 to 6;

Fig. 8 is a view of the under side of the bed of the machine of the surface immediately under the assembling plunger, showing the detail of the can end lifting pad trigger slide;

Figs. 9 and 10 are views of a trigger operating bar;

Fig. 11 is a horizontal section on line 11-11 in Fig. 6; and

Figs. 12 and 13 are horizontal sections immediately under the top plate at the assembling station, showing in detail, the means for holding and centering the can ends relative to the positioned cut gasket in the orifice above.

The embodiment of the invention shown on the drawing comprises a head 1 supporting and guiding a plunger 2, which is operated by a foot lever 3, through connecting link 4 and lever 5, which is fulcrumed at the rear end of the head 1, the plunger, both levers and the connecting link being counterbalanced by a weight 6. The head 1 is mounted on a table or bed, the top surface of which consists of two bed plates 7 and 8 arranged at different heights, the lower plate 8 extending under the upper plate 7 at the center 9 at the front and therebeyond connecting with an incline 10, which extends to the left front corner 11 of the machine.

Immediately under and in alinement with the plunger 2 is a partial circular aperture

12 in the upper plate 7 for gaskets 18, this aperture being partial in the sense that nearly 90° of its right front surrounding section is cut away at 13. Below the level 5 of the upper surface of the upper plate 7 in the circular part of the aperture 12 is a supporting rib 14 to hold the gaskets 18 after they are located ready for assembling. Where the lower plate 8 passes under the 10 upper plate 7 near the center of the front of the machine, are secured two can end positioning pins 15 and 16. A spring 17 is secured at one end to the left front edge of the lower plate 8 and in conjunction with 15 the pins 15 and 16 positions and holds can ends 19 in alinement with the plunger 2 and aperture 12 ready to receive a gasket liner. Let into the lower plate 8 and in alinement with the plunger 2 and aperture 12 is a can 20 end lifting pad 20, which is normally held down with its upper face flush with the upper surface of the lower plate 8 by a slideable trigger 21, which engages with an angular groove 23 in the pad stem. The pad 20 is 25 forced up by an open helical spring 22 when the trigger is released. The trigger 21 is a plate with an elongated opening 24, one end of which is beveled to engage in a groove 23 in the stem 20' of the pad 20 and the inner end of the plate has a projection 25 at one side upon which is revolvably mounted a roller 26. The trigger 21 is normally held 30 in engagement with the angular groove 23 by an open helical spring 27. The trigger 35 21 is movably held in its seat by a gibbing plate 28, which has across its inner end an angular upward projection 29. A trigger operating bar 30 is pivoted to the lever 5 back of where the lever 5 is pivoted to the 40 plunger 2 and hangs down through opening 31 in the head 1. This bar has a cam shaped lower end 32 normally gravitating into contact with the gibbing plate projection 29, its extreme end being a little above the roller 45 26 when plunger 2 is at its highest position shown in Fig. 3.

At the left of the center 9 of the front on the lower plate 8 and extending the length 50 of the incline 10 is a can end guide strip 33, and at the lower end of the incline 10 is an orifice 34. A small shelf 35 is secured to the left front leg. A can end stack 36 is located on the shelf 35 in alinement with orifice 34. In the operation of the machine, the 55 gaskets 18 are placed on the plate 7, and the can ends 19 are placed on the plate 8, both in superimposed relation with edges overlapping, as shown on the drawing, so that the top one may be drawn off readily 60 by the finger tips.

The operator seated in front of the machine, using both hands simultaneously, places the finger tips of the left hand on the front overlapping portion of the top 65 gasket 18 (see Fig. 1), and through fric-

tional contact of fingers draws it from the pile across the surface of the plate 7 to the front of the machine and places it in aperture 12, resting it on supporting rib 14 (see Fig. 2) and at the same time, with the finger tips of the right hand, does likewise with the can end 19 (see Fig. 1), sliding it across the surface of the plate 8 in front of the positioning pin 15 until it is located by the positioning pins 15 and 16 and spring 17, the fingers having ample operating room in the cut away portion at 13 of the plate 7 (see Fig. 2-12 and 13). This can end thus positioned displaces the last assembled can end and pushes the same through between 70 the spring 17 and the positioning pin 16 into the space between the shoulder 37 and the guide strip 33 (see Fig. 12). This in turn displaces a can end previously assembled, pushing the same onto the incline 10 75 down which it will gravitate between the guide strip 33 and the shoulder 37 and fall through the orifice 34 (see Fig. 12) onto the stack 36 (see Fig. 2).

When the hands have been withdrawn 80 and are reaching for the next gasket and can end, the operator depresses the foot lever 3 with the foot and in so doing, through the link 4, depresses the lever 5, forcing down the plunger 2 and the trigger 90 operating rod 30. When the plunger has been forced down about one third of the way to the upper surface of the upper plate 7, the cam shaped end 32 of the trigger rod 30, acting against the fixed angular projection 29 of the gibbing plate, will force the trigger forward (see Fig. 4) releasing the can end lifting pad 20, which is at once lifted by the spring 22 carrying up the positioned can end 19 until the curled edge of 100 the can end contacts with the lower edge of the circular part of the aperture 12. The plunger 2 continuing down contacts with the gasket 18 resting on the supporting rib 14 and snaps it past the rib 14 into the full 105 sized circular portion of the aperture 12 below the supporting rib 14, and then snaps it past the curled edge of the can end 19 into the bottom of the annular groove formed by the curled edge and shoulder of the can 110 end 19. The continued downward motion of the plunger carries down the gasket 18, the can end 19 and the can end lifting pad 20 until the top of the lifting pad 20 is flush again with the surface of the plate 8. At 115 this time the trigger rod 30 has moved down so that the upper part of the cam shaped end 32 has passed below the plane of the trigger roller 26. The roller 26, under the influence of the spring 27 acting on plate 120 29, now passes through an opening 38 provided for the purpose above the cam part 32. This movement results in the reengagement 125 of the trigger in the angular groove 23 to hold the pad 20 in position to receive the next 130

- can end. This having been accomplished, the operator removes or raises his foot from the foot lever 3, allowing counterweight 6 to return the various parts to their normal position. In returning to its normal position the cam shaped end 32 of the trigger rod 30 passes between the body of the trigger plate 21 and the trigger roller 26. When the lever 5 and the plunger 2 have resumed their normal position the cam shaped end 32 of the trigger rod 30 gravitates over the trigger roller 26 into contact with the angular projection 29 in position for the next cycle of movements.
- 15 It is thought that the invention and many of its attendant advantages will be understood from the foregoing description, and it will be apparent that various changes may be made in the form, construction and arrangement of the parts without departing from the spirit and scope of the invention or sacrificing any of its material advantages, the form hereinbefore described being merely a preferred embodiment thereof.
- 20 I claim:
1. A machine for assembling thin, annular gaskets with flanged and shouldered can ends, comprising in combination a bed having a shouldered aperture arranged to permit an operator to deposit a gasket therein, a can end support beneath said aperture and arranged to permit an operator to deposit a can end thereon in axial alinement with the gasket in said aperture, centering means yieldable in a radial direction relative to the can end and engageable with the edge of the can end and a plunger operable at will for assembling said gasket and said can end.
  2. A machine for assembling thin, annular gaskets with flanged and shouldered can ends, comprising in combination superposed gasket and can end holding means arranged to permit an operator to manually place a gasket and can end therein respectively, and a plunger for moving said gasket toward said can end in assembling said gasket and can end, a spring actuated plunger for lifting the can end, and means for holding down said spring actuated plunger while the can end is being placed.
  3. A machine for assembling thin, annular gaskets with flanged and shouldered can ends, comprising in combination superposed gasket and can end holding means arranged to permit an operator to manually place a gasket and can end therein respectively, said can end holding means having devices for yieldably engaging the edge of the can end, and a plunger for moving said can end toward said gasket in assembling said can end and said gasket.
  4. A machine for assembling thin, annular gaskets with flanged and shouldered can ends, comprising in combination super-
- posed gasket and can end holding means arranged to permit an operator to manually place a gasket and can end therein respectively, centering devices including means yieldable radially relative to the can end 70 and engageable with the edge of the can end, and means moving said gasket and can end toward each other in assembling said gasket and can end.
5. A machine for assembling thin, annular gaskets with flanged and shouldered can ends, comprising in combination means for receiving a gasket liner and a can end in spaced relation and both manually delivered, a spring actuated plunger for lifting the can end, a foot operated plunger for assembling said gasket and said can end when held in said means and for depressing the spring-actuated plunger, devices for locking down the latter, and means for releasing said locking devices.
6. A machine for assembling thin annular gaskets with flanged and shouldered can ends, comprising in combination a bed arranged to support at one hand of the operator a plurality of gaskets and at the other hand can ends, spread out in separate piles, said bed being flat and exposed for the sweeping movement of the hands of the operator thereover, an assembling station 95 having an opening accessible by the hands of the operator from opposite sides of the opening and comprising centering means for holding separately a gasket and can end 100 in alined relation, and a plunger operable at will for assembling said gasket and end when in alinement at said assembling station.
7. A machine for assembling thin, annular gaskets with flanged and shouldered can ends, comprising in combination a bed having a centrally disposed assembling station and horizontally extended feed surfaces arranged to support horizontally extended piles of superposed gaskets and can ends 110 located respectively on opposite sides of said assembling station within easy reach of an operator, said feed surfaces being at different levels and exposed for the sweeping movement of the hands of the operator thereover to the assembling station, and the assembling station being accessible by the hands of the operator from opposite sides of the same, means at the assembling station for receiving a can end and a gasket from 120 the hands of an operator and positioning them in alinement, and a plunger for assembling said gasket and can end.
8. A machine for assembling thin annular gaskets with flanged and shouldered can ends, comprising in combination a bed arranged to support at one hand of the operator a plurality of gaskets and at the other hand can ends, spread out in separate piles, said bed being flat and exposed for the 130

sweeping movement of the hands of the operator thereover, an assembling station having an opening accessible by the hands of the operator from opposite sides of the opening and comprising means for holding a gasket and can end in alined relation, a plunger operable at will for assembling said gasket and end when in alinement at said assembling station, a spring-actuated lifter 10 for raising the can end toward the plunger, means for holding down said lifter, and means for releasing the lifter.

9. A machine for assembling thin annular gaskets with flanged and shouldered can ends, comprising in combination a bed arranged to support at one hand of the operator a plurality of gaskets and at the other hand can ends, spread out in separate piles, said bed being flat and exposed for the sweeping movement of the hands of the operator thereover, an assembling station having an opening accessible by the hands of the operator from opposite sides of the opening and comprising centering means for holding separately a gasket and can end in alined relation, a plunger operable at will for assembling said gasket and end when in alinement at said assembling station, and a lateral discharge slide for the lined can end.

10. A machine for assembling thin annular gaskets with flanged and shouldered can ends, comprising in combination a bed arranged to support at one hand of the operator a plurality of gaskets and at the other hand can ends, spread out in separate piles, said bed being flat and exposed for the sweeping movement of the hands of the operator thereover, an assembling station having an opening accessible by the hands of the operator from opposite sides of the opening and comprising centering means for holding separately a gasket and can end in alined relation, a plunger operable at will for assembling said gasket and end when in alinement at said assembling station, a shoulder in said opening for supporting the gasket, a lifter for moving the can end toward the supported gasket, means for raising the lifter, a lateral discharge way for the lined can end, and means for holding the lifter with the lined can end in line with said discharge way.

11. A machine for assembling thin, annular gaskets with flanged and shouldered can ends, comprising in combination a bed having a centrally disposed assembling station and horizontally extended feed surfaces arranged to support horizontally extended piles of superposed gaskets and can ends located respectively on opposite sides of said assembling station within easy reach of an operator, said feed surfaces being at different levels and exposed for the sweeping movement of the hands of the operator 55 thereover to the assembling station, and the assembling station being accessible by the hands of the operator from opposite sides of the same, means at the assembling station for receiving a can end and a gasket from the hands of an operator and positioning them in alinement, a plunger for assembling said gasket and can end, a spring actuated lifter which is depressible by the plunger, means for holding down the lifter, a treadle for actuating the plunger and said holding down means, and a lateral discharge way for the lined can end which is arranged at substantially the level of the lower can end feed surface and of the depressed lifter.

thereover to the assembling station, and the assembling station being accessible by the hands of the operator from opposite sides of the same, means at the assembling station for receiving a can end and a gasket from the hands of an operator and positioning them in alinement, a plunger for assembling said gasket and can end, and a lateral discharge way for the lined can end at substantially the level of the lower feed surface 75 along which the unlined can ends are fed.

12. A machine for assembling thin annular gaskets with flanged and shouldered can ends, comprising in combination a bed having a centrally disposed assembling station 80 and horizontally extended feed surfaces arranged to support horizontally extended piles of superposed gaskets and can ends located respectively on opposite sides of said assembling station within easy reach of an operator, said feed surfaces being at different levels and exposed for the sweeping movement of the hands of the operator thereover to the assembling station, and the assembling station being accessible by the hands of the operator from opposite sides of the same, means at the assembling station for receiving a can end and a gasket from the hands of an operator and positioning them in alinement, a plunger for assembling 90 said gasket and can end, a lateral discharge way for the lined can end arranged to be depressed by the plunger, a treadle for actuating the plunger, and means controlled by the treadle 100 for holding the lifter at substantially the level of the lower feed surface and of said discharge way.

13. A machine for assembling thin, annular gaskets with flanged and shouldered can 105 ends, comprising in combination a bed having a centrally disposed assembling station and horizontally extended feed surfaces arranged to support horizontally extended piles of superposed gaskets and can ends located respectively on opposite sides of said assembling station within easy reach of an operator, said feed surfaces being at different levels and exposed for the sweeping movement of the hands of the operator 115 thereover to the assembling station, and the assembling station being accessible by the hands of the operator from opposite sides of the same, means at the assembling station for receiving a can end and a gasket from the hands of an operator and positioning them in alinement, a plunger for assembling 120 said gasket and can end, a spring actuated lifter which is depressible by the plunger, means for holding down the lifter, a treadle for actuating the plunger and said holding down means, and a lateral discharge way for the lined can end which is arranged at substantially the level of the lower can end feed surface and of the depressed lifter.

14. A method of applying gasket liners to flanged and shouldered can ends, which consists in placing at the two hands of and in front of the operator and at opposite 5 sides of an assembling station the ring liners and can ends respectively in horizontally extended piles of superposed articles, manually selecting a gasket and a can end from said conveniently arranged sources of supply and manually sliding them toward each 10 other to said assembling station and depositing them in holding devices and in spaced

axial alinement, and thereafter assembling the same by axial pressure set in operation by the foot of the operator while the hands 15 are selecting another gasket and a can end for subsequent placing in said holding devices.
